RADIO AND TELEVISION ANTENNA

Cesare Saranga, New Rochelle, N. Y.

Application September 28, 1951, Serial No. 248,697

9 Claims. (Cl. 250—33.53)

1

This invention relates to antennas, and more particularly to an indoor television antenna.

The main object of the invention is to provide a novel and improved antenna suitable for use with television and other relatively high frequency radio receivers, the improved antenna being simple in construction, being relatively compact in size, and being substantially omnidirectional.

A further object of the invention is to provide an improved indoor antenna particularly suitable for use with television receivers, said antenna being arranged to function satisfactorily on both the low frequency and high frequency television bands, providing a reduction in interference, being substantially omnidirectional, whereby it is ordinarily not necessary to rotate the antenna to receive a television signal with satisfactory intensity, being inexpensive to manufacture, and being attractive in appearance.

A still further object of the invention is to provide an improved indoor television antenna which is arranged to provide substantially balanced performance on both the high frequency and low frequency television bands, the antenna involving only simple, inexpensively fabricated parts, being sturdy in construction, and being arranged to provide satisfactory reception of all television channels without requiring the antenna, in most cases, to be especially oriented to receive any particular channel.

Further objects and advantages of the invention will become apparent from the following description and claims, and from the accompanying drawings, wherein:

Figure 1 is a perspective view of an improved radio and television antenna constructed in accordance with the present invention.

Figure 2 is a vertical cross sectional view taken on the line 2—2 of Figure 1.

Figure 3 is a vertical cross sectional view taken on the line 3—3 of Figure 1.

Figure 4 is a schematic wiring diagram showing the electrical connections of the various elements of the antenna of Figures 1 to 3.

Referring to the drawings, the complete antenna assembly is designated generally at 11. The antenna assembly comprises a base 12 comprising the mating elements 13 and 14 of insulating material. The element 13 has an upstanding, generally circular integral portion 15 and the element 14 has an upstanding, generally circular integral portion 16, the portions 15 and 16 being secured together by a transverse bolt 17, as shown in Figure 3. When the elements 13 and

2

14 are clamped together by the bolt 17, it will be seen that a hollow space is defined under the member 12, said hollow space including the cavity defined between the opposing inclined circular upstanding elements 15 and 16.

Molded in the respective elements 13 and 14 adjacent the base portions of the upstanding elements 15 and 16 are the lower ends of respective upwardly projecting, substantially semicircular arms 18 and 19, said arms 18 and 19 being formed from suitable conductive rod material, as for example from metal tubing, the semicircular arms 18 and 19 being arranged in coplanar relation and being rigidly connected together at their top ends by an arcuate connecting bar 20 of insulating material. As shown in Figure 3, with the arms 18 and 19 connected, said arms define with the insulating bar 20 a substantially circular loop of relatively large diameter having the insulating bar 20 located at its top ends.

Rigidly secured to the upper portions of the respective arms 18 and 19 are the respective pairs of conductive stubs 21 and 22 and 23 and 24. As shown in Figure 3, said conductive stubs 21, 22 and 23, 24 extend upwardly and outwardly from the respective arms 18 and 19 on opposite sides of the base 12, the arms 21 and 22 being spaced apart on the arm 18 and the arms 23 and 24 being spaced apart on the arm 19 in the manner shown in Figure 3, the arms 21 and 23 being relatively short as compared with the arms 22 and 24.

The circular loop defined by the arms 18 and 19 preferably has a diameter of the order of at least 12 inches, the arms 22 and 24 being of a length of approximately 18 inches and the arms 21 and 23 being of a length of approximately 8 inches. The length of the insulating bar 20 is approximately 1½ inches, and the ends of said insulating bar may be secured to the top ends of arms 18 and 19 by being frictionally engaged in the top ends of said arms.

Designated at 25 and 26 are respective terminals secured in the horizontal portions of the base sections 13 and 14, the respective lower ends 45 of the arms 18 and 19 being connected by short wires 27 and 28 to the respective terminals 25 and 26.

Designated at 29 is a circular loop of conductive rod material, such as metal tubing, whose lower ends are rigidly clamped between the upper portions of the insulating disc elements 15 and 16, rigidly securing the loop 29 in the meeting plane between base sections 13 and 14, said meeting plane extending at right angles to the vertical plane defined by the arms 18 and 19.

The loop 29 is thus contained within the circular loop defined by arms 18 and 19 and the top connecting bar 20, the loop 29 being relatively small in diameter as compared with the circular loop defined by elements 18, 19 and 20. For example, the loop 29 may be approximately six inches in diameter. As shown in Figure 1, loop 29 extends in a vertical transverse plane which intersects the vertical plane defined by elements 18, 19 and 20 at right angles and at the vertical center line of the antenna assembly.

Disposed in the upper portion of the cavity defined between the opposing circular elements 15 and 16 is a capacitor 33 having a capacitance of about .002 mf. which is connected between the ends of the inner loop 29, as shown in Figure 4. Designated at 31 is another capacitor which is disposed in the cavity between disc elements 15 and 16, said capacitor being connected between one end of the loop 29 and the lower end of the semicircular arm 19. Capacitor 31 has a capacitance of approximately .01 mf.

It will thus be seen that the arms 18 and 19 are connected respectively to the terminals 25 and 26 and may be considered as the respective elements of a dipole array having an electrical length approximately that required to resonate to the center of the lower television frequency band, whereas the loop 29 may be considered as an unbalanced signal collector having electrical characteristics which apparently cause the loop 29 to be resonant to frequencies in the upper television band. The relatively large capacitor 31 couples the loop 29 to the antenna terminal 26 and the capacitor 30 provides a compensating effect to improve the matching of the antenna to the transmission lines 32 and 33 connecting the antenna terminals to a television receiver, such as the receiver shown at 34. The lines 32 and 33 are preferably the conductors of conventional 300 ohm twin lead transmission line, and the length of the transmission line is preferably of the order of six feet.

While the exact theory of operation of the antenna array above described is not entirely clear, it is believed that the loop 29 and capacitor 30, together with the distributed capacitance to ground of loop 29 defines a band pass filter for the low frequency television signals while at the same time serving efficiently as a signal collector for the high frequency television signals. It is further believed that the semicircular arms 18 and 19, together with their distributed capacitance to ground define a band pass filter for the high frequency television signals as well as serving as an efficient dipole array for the low frequency television signals, the dipole effect being reinforced and augmented by the respective pairs of stubs 21 and 22, and 23, 24 provided on the respective dipole arms 18 and 19. The combination of the characteristics above described apparently results in an over-all array which is substantially omnidirectional and which is substantially equally efficient for both the low frequency band of television signals and the high frequency band of television signals, whereby the antenna may be employed to receive television signals over the entire range of frequencies now in use without requiring any substantial change in orientation of the antenna when the receiver 34 is switched from one channel to another. By actual trial it has been found that in only the case of weak signals at the upper end of the high frequency band is it necessary to modify the orientation of the antenna after it has been

once positioned adjacent to the television receiver with which it is to be employed.

While a specific embodiment of an improved radio and television antenna has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An antenna of the character described comprising an insulating base, a pair of coplanar rigid conductive arms, insulated from each other, secured to said base and projecting upwardly therefrom on opposite sides of said base, a rigid conductive loop secured to said base between said arms in a vertical plane at a substantial angle to the plane of said arms, and means capacitively coupling said loop to one of said arms.

2. An antenna of the character described comprising an insulating base, a pair of coplanar rigid conductive arms, insulated from each other, secured to said base and projecting upwardly therefrom on opposite sides of said base, a rigid conductive loop secured to said base between said arms in a plane at a substantial angle to the plane of said arms, means coupling said loop to the lower end of one of said arms, and a pair of terminals connected respectively to the lower ends of said arms.

3. An antenna of the character described comprising an insulating base, a pair of rigid coplanar conductive arms, insulated from each other, secured to said base and projecting upwardly therefrom on opposite sides of said base, a rigid conductive loop secured to said base between said arms in a vertical plane at right angles to the plane of said arms, and means capacitively coupling said loop to one of said arms.

4. An antenna of the character described comprising an insulating base, a pair of rigid coplanar opposing arcuate conductive arms, insulated from each other, secured to said base and projecting upwardly therefrom on opposite sides of said base, a rigid circular conductive loop of much smaller radius than said arms secured to said base between said arms in a vertical plane at right angles to the plane of said arms, and means capacitively coupling said loop to the end of one of said arms.

5. An antenna of the character described comprising an insulating base, a pair of rigid coplanar opposing arcuate conductive arms secured to said base and projecting upwardly therefrom on opposite sides of said base, a rigid circular conductive loop of much smaller radius than said arms secured to said base between said arms in a vertical plane at right angles to the plane of said arms, a capacitance connected in said loop, and means capacitively coupling one end of said loop to one of said arms.

6. An antenna of the character described comprising an insulating base, a pair of rigid coplanar opposing arcuate conductive arms secured to said base and projecting upwardly therefrom on opposite sides of said base, an insulating bar rigidly connecting the top ends of said arms, a rigid circular conductive loop of much smaller radius than said arms secured to said base between said arms in a vertical plane at right angles to the plane of said arms, a capacitance connected in said loop, and means capacitively coupling said loop to the lower end of one of said arms.

7. An antenna of the character described comprising an insulating base, a pair of rigid coplanar, opposing, arcuate conductive arms secured to said base and projecting upwardly therefrom on opposite sides of said base, an insulating bar rigidly connecting the top ends of said arms, respective, relatively short conductive bars rigidly secured to said arms and projecting upwardly and outwardly from said arms in the same plane therewith, a rigid circular conductive loop of much smaller radius than said arms secured to said base between said arms in a vertical plane at right angles to the plane of said arms, a capacitance connected in said loop, and means capacitively coupling one end of said loop to the lower end of one of said arms.

8. An antenna of the character described comprising a base of insulating material, respective opposing semicircular conductive arms secured rigidly to said base and projecting upwardly therefrom in a common vertical plane, an insulating bar rigidly connecting the top ends of said arms, a plurality of relatively short, straight, spaced conductive bars secured to each arm and projecting upwardly and outwardly therefrom in the same plane as said arms, said conductive bars being of different lengths, a rigid circular conductive loop secured to said base in a vertical plane at right angles to the plane of said arms, a capacitance in said base connected between the ends of said loop, another capacitance in said base connecting one end of said loop to the bottom end of one of said arms, and a pair of output terminals connected respectively to the bottom ends of said arms.

9. An antenna of the character described comprising a base of insulating material, respective opposing semicircular conductor arms secured rigidly to said base and projecting upwardly therefrom in a common vertical plane, an insulating bar rigidly connecting the top ends of said arms a plurality of relatively short, straight, spaced conductive bars secured to the upper portion of each arm and projecting upwardly and outwardly therefrom in the same plane as said arms, said conductive bars being of different lengths, a rigid circular conductive loop secured to said base in a vertical plane at right angles to the plane of said arms, said loop being of much smaller radius than said arms, a capacitance in said base connected between the ends of said loop, another capacitance in said base connecting one end of said loop to the bottom end of one of said arms, and a pair of output terminals connected respectively to the bottom ends of said arms.
